UNITED STATES PATENT OFFICE

148,847

DESIGN FOR A GAME BOARD

Harvey M. Fisher and Milton A. Barnett,
St. Louis, Mo.

Application November 6, 1946, Serial No. 134,558

Term of patent 3½ years

(Cl. D34—5)

To all whom it may concern:

Be it known that Milton A. Barnett and Harvey M. Fisher, citizens of the United States residing at St. Louis, in the county of Independent City and State of Missouri, have invented a new, original, and ornamental Design for a Game Board, of which the following is a specification, reference being had therein to the accompanying drawing, forming part thereof, in which:

Figure 1 is a top plan view of a game board, showing our new design.

Figure 2 is a view in end elevation.

Parts of the drawing are lined for colors.

The essential characteristics of this design reside in the wavy line encircling the four-way checker board, and in the four figure designs at the four corners of the checker board, said four

designs interrupting said wavy line as shown.

We claim:

The ornamental design for a game board, as shown and described.

HARVEY M. FISHER.
MILTON A. BARNETT.
